UNITED STATES PATENT OFFICE

JAMES J. CARFREY, OF PHILADELPHIA, PENNSYLVANIA, ASSIGNOR TO GOTHAM SILK HOSIERY COMPANY, INC., OF PHILADELPHIA, PENNSYLVANIA, A CORPORATION OF DELAWARE

RUNNER STOP FOR STOCKINGS

Application filed December 20, 1928. Serial No. 327,371.

This invention relates to means for preventing runners from advancing beyond a predetermined line in a knitted stocking.

The invention is particularly adapted to preventing runners from advancing from the welt of the stocking into the leg thereof, and from the leg into the welt of the stocking.

When a stitch in the fabric breaks it releases the loop of the next successive stitch in the particular wale of the fabric in which the broken stitch is located.

A stocking when being worn is under tension, thus, when a stitch breaks this tension will cause the stitches of that particular wale to become unlooped successively and this unlooping of the stitches will continue or advance along the length of that particular wale, thereby producing what is commonly termed a "runner".

Runners will not advance when the fabric is not under tension, therefore, the object of this invention is to create an area or to form a band in the stocking fabric extending coursewise around the stocking which will at all times be free from tension, including such times as the stocking is being worn and is subjected to the usual tension applied thereto for the purpose of preventing the stocking from wrinkling.

The unstressed band is formed by introducing a supplementary thread into the fabric which is looped back and forth across the predetermined area of the fabric which is to form the unstressed band, the said supplementary thread passing through the stitches of the wales of the fabric, interlocking with these said stitches and being itself interlocked with a second supplementary thread on the opposite face of the fabric.

The first mentioned supplementary thread by interlocking with the stitches of the fabric prevents a runner advancing beyond the stitches with which the said supplementary thread is interlocked, and the loops formed by this said supplementary thread passing back and forth across or bridging the unstressed area assume the tension, direct from the stitches of the fabric located at the opposite sides of the unstressed area or band, which would normally be assumed

by the stitches lying within the said unstressed or neutral band. Therefore, should a runner advance to one side of the unstressed band it will be stopped by the lack of tension within the said band and also by the tension assuming supplementary threads which are interlocked with the stitches immediately adjacent the unstressed band in the stocking.

The said second supplementary thread passes back and forth across the unstressed band on the opposite face of the fabric from that which is occupied by the first said supplementary thread and also assists in assuming the tension. This second supplementary thread also binds the portion of the fabric which constitutes the unstressed band tightly against the backs of the loops of the first said supplementary threads, and this binding in the unstressed fabric causes the loops of this part of the fabric to be pressed tightly together and to frictionally engage each other and thereby contribute to the general results, i. e. the preventing of a runner advancing across the stop line created by the nonstressed band.

Referring to the drawings:

Fig. 1 is a side view of a stocking equipped with my invention;

Fig. 2 is an enlarged diagrammatic section taken on the line 2—2, Fig. 1.

Fig. 3 is a view similar to Fig. 2, but illustrating the welt portion of the stocking folded against the leg portion thereof in the manner assumed while the supplementary threads are being introduced into the fabric;

Figs. 4 and 5 are elevations looking at the opposite faces, respectively, of the fabric as it appears in Fig. 3;

Fig. 6 is a plan view of the fabric as it appears in Fig. 3;

Fig. 7 is an enlarged diagrammatic view showing the stitch formation and the manner in which the said supplementary threads interlock with the fabric stitches and with each other;

Fig. 8 is a diagrammatic section taken on the line 8—8, Fig. 7; and

Fig. 9 is a view similar to Fig. 8, but

showing the courses of stitches which constitute the unstressed band as being bound in closely by and between the supplementary threads located on the opposite faces of the fabric.

5 Figure 1 shows a stocking of ordinary construction and comprising a leg portion 1, the top portion of which is folded and its extreme edge secured to the leg portion at the point 2, to form a turned welt 3, composed of an outer fold 4 and an inner fold 5.

10 As shown in Fig. 7, the fabric of which the stocking is composed is formed of a plurality of courses of stitches 10 comprising needles loops 11 and sinker loops 12.

15 The stitches 13 of the course at the edge of the inner fold 5 of the turned welt 3 are, in the present instance, interknit with one of the courses of stitches 10 of the leg portion 1 in the usual manner.

20 In order to form the nonstressed band 20, which forms the subject of this invention, the stocking after being knit is folded, preferably along the line where the welt 3 joins the leg 1, as clearly shown in Fig. 3.

25 The stocking fabric folded in this manner is then run through a suitable machine, for example, an ordinary seaming machine, by the mechanism of which the supplementary thread 25 is successively passed through the leg portion 1, and through the outer fold 4 and the inner fold 5 of the welt, at spaced intervals across the fabric, forming loops 26 and 27 respectively at the opposite sides of the folded fabric.

30 Through each adjacent pair of the loops 26, and then through an adjacent pair of the loops 27, in alternating succession, is passed the second supplementary thread 30 which, as shown in the drawings, especially in Fig. 6, interlocks with the first supplementary thread 25 and prevents the thread 25 from being pulled out of the fabric.

35 As shown in Fig. 7, the supplementary thread 25 passes through the needle loops 11 of the stitches 10 on one side of the unstressed band 20 and through the sinker loops 12 of the stitches 10 at the opposite

40 side of the unstressed band 20. However, this is not essential and the supplementary thread 25 may pass through either the needle loops 11 or the sinker loops 12 at either or both sides of the unstressed area. This condition depends entirely upon the manner in which the folded fabric is presented to the thread inserting elements of the seaming machine and also depends upon the number of wales per inch across the fabric, the

45 rate of speed per minute at which the fabric is passed through the seaming machine, and the number of times per minute that the machine operates to pass the thread 25 through the folded fabric.

50 After the supplementary threads 25 and

30 have been inserted the fabric is straightened out in the manner illustrated in Figs. 1 and 2. The substantially straight portions 25a and 30a of the threads 25 and 30 respectively then bridge the unstressed area 70 or band 20 and thereby assume all strain and tension which would normally be taken by the stitches lying within the area 20.

55 As shown in Fig. 9, these stitches are bound in tightly between the straight portions 25a and 30a of the threads 25 and 30 respectively, and are caused to frictionally engage each other thereby assisting in the final result, that of preventing a runner 80 from advancing through the unstressed area of the fabric.

60 This invention is adaptable to stockings produced by either flat or circular knitting machines in which the edge of the welt is interknit with the stitches of the leg, and 85 also to stockings knit on a circular knitting machine wherein there is no turned welt formed on the stocking.

65 A turned welt may be produced by folding the stocking in the manner indicated in Fig. 3 and passing the supplementary thread 25 through the three layers of fabric, as also noted, in which case the supplementary threads 25 and 30 will not only act to prevent the advancement of runners, as above 90 noted, but will also function as a means for securing the top edge of the stocking to the leg portion thereof to produce a turned welt on the stocking.

70 The unstressed band 20, in the present instance and as clearly shown in the drawings, is in the form of a tuck, wherein the one supplemental thread 25 functions to join the folds of such tuck at its base, and appears on one face of the fabric, and the second supplemental thread 30 interlocks with the first supplemental thread 25 and passes across the fabric included within the tuck on the opposite face of the fabric, thereby binding the stitches, of which the fabric within the 100 tuck is formed, tightly together between the threads 25 and 30 in the manner illustrated in Fig. 9.

75 I claim:

1. The combination with a knitted stocking of a tuck formed in and extending coursewise of the stocking fabric after the knitting thereof for preventing runners which are advancing in a walewise direction from either side of and toward a predetermined 115 line produced by the formation of said tuck from crossing said predetermined line to the opposite side thereof, said tuck forming a band of unstressed fabric at said predetermined line and means bridging said unstressed band and adapted to assume any tension applied to the stocking, whereby said band is at all times relieved of said tension, said bridging means comprising a supplementary thread looped back and forth across 120

125

130

said band and interlocking with the stitches of the stocking fabric at the opposite sides of said band.

2. The combination with a knitted stocking of a tuck formed in and extending coursewise of the stocking fabric after the knitting thereof for preventing runners which are advancing in a walewise direction from either side of and toward a predetermined line produced by the formation of said tuck from crossing said predetermined line to the opposite side thereof, said tuck forming a band of unstressed fabric at said predetermined line and means bridging said unstressed band and adapted to assume any tension applied to the stocking, whereby said band is at all times relieved of said tension, said bridging means comprising a supplementary thread looped back and forth across said band on one face of the stocking fabric and interlocked with the stitches of the stocking fabric at the opposite sides of said band, and a second supplementary thread looped back and forth across the said band on the opposite face of said fabric and interlocked with the first said supplementary thread at the opposite sides of said band.

3. The combination with a knitted stocking of a tuck formed in and extending coursewise of the stocking fabric after the knitting thereof for preventing runners which are advancing in a walewise direction from either side of and toward a predetermined line produced by the formation of said tuck from crossing said predetermined line to the opposite side thereof, said tuck forming a band of unstressed fabric at said predetermined line and means bridging said unstressed band and adapted to assume any tension applied to the stocking, whereby said band is at all times relieved of said tension, said bridging means comprising a supplementary thread looped back and forth across said band on one face of the stocking fabric and interlocked with the stitches of the stocking fabric at the opposite sides of said band, and a second supplementary thread looped back and forth across the said band on the opposite face of said fabric and interlocked with the first said supplementary thread at the opposite sides of said band, the stitches of the fabric of which the tuck is composed being bound in frictional contact with each other by and between the first and second mentioned supplementary threads.

4. A process for producing a runner stop-line in a knitted fabric, which comprises the folding of the fabric on a line extending coursewise of the fabric, passing a supplementary thread through the stitches of which the folds of the fabric are composed at a point removed from the edge formed by the folding of the fabric, forming loops in the supplementary thread at

each side of the folded fabric, passing a second supplementary thread through the loops formed in the first supplementary thread at each side of the folded fabric, said second thread passing back and forth over the edge formed by the folding of the fabric between and interlocking with the said loops of the first said supplementary thread subsequently unfolding the fabric, whereupon the said supplementary threads will assume any tension applied to the fabric in a walewise direction, permitting that portion of the fabric lying between the points where the said first supplementary thread passes through the fabric to remain in an unstressed condition, said first and second said supplementary threads co-operatively binding the stitches forming the unstressed portion of the fabric in frictional engagement with each other.

5. A knitted stocking composed of stitches formed of a primary thread, an unstressed band extending coursewise thereof and functioning as a runner stop, said band consisting of a tuck formed in the stocking fabric, a supplementary thread passing through the stocking fabric at the base of the tuck, and a second supplementary thread interlocked with the first supplementary thread and binding the tuck tightly therebetween.
